UNITED STATES PATENT OFFICE.

JOHN SORENSEN, OF OTTAWA, ILLINOIS.

RADIATOR CORE.

1,414,440.

Specification of Letters Patent.

Patented May 2, 1922.

Application filed October 4, 1920. Serial No. 414,499.

To all whom it may concern:

Be it known that I, JOHN SORENSEN, a citizen of the United States, residing at Ottawa, in the county of La Salle and State of Illinois, have invented a certain new and useful Improvement in Radiator Cores, of which the following is a full, clear, concise, and exact description, reference being had to the accompanying drawings, forming a part of this specification.

This invention relates to radiator cores, and more particularly to a radiator core having spaced continuous tortuous water passages extending from top to bottom of said radiator, and intervening air passages provided with partitions that act as deflector plates for the air passing through said passages so as to cause the air to have a greater cooling effect on the water in the said radiator.

It is a purpose of the invention to provide a radiator core having the above mentioned characteristics, that is, made up of pairs of sheet metal members forming a water passage between them, alternating with spacing reinforcing members that serve as deflector partitions in said air passages.

It is a further purpose of this invention to provide a radiator core having continuous water passages extending from top to bottom thereof, the walls of said water passages being formed by a pair of sheet metal members that are provided with arcuate corrugations curved downwardly from the center toward the front and rear ends of said core, which water passages alternate with air passages having partitions therein comprising sheet metal members provided with arcuate corrugations extending in a direction opposite to that of the corrugations of the members forming the walls of said water passages.

It is another object of the invention to provide a radiator core with water containing members that are each made up of a pair of corrugated sheet metal members that are made alike but merely faced in opposite directions to form a water passage between them. This is accomplished by corrugating the edge portions more deeply than the central portions of the sheet metal members.

It is a further purpose of the invention to provide means in the air passages of said radiator core that serve to compensate for the expansion of said water chambers due

to freezing or other causes, and cause said water passages to resume their original shape and position after the expansion force is removed.

It is a still further object of the invention to provide a radiator core having tortuous air and water passages that are so constructed that there will be no possibility of clogging either of these passages by any foreign matter that may pass therethrough, and to provide a radiator core that can be readily cleaned.

It is also a further purpose of the invention to provide a radiator core with separating or air deflecting elements whose edge portions are corrugated deeper than the central curved portion thereof, thus causing an excess of material in the central curved portion, which causes these elements to return to normal position after flattening to a certain extent due to the expansion of the water containing member when freezing. This causes the radiator to return to normal condition after freezing and consequently prevents leakage.

Other objects and advantages of the invention will appear as the description of the accompanying drawings having one form that my invention may take, proceeds. However, I desire to have it distinctly understood that I do not intend to limit myself to the exact details shown therein and described in the specification, but desire to include as part of my invention all such obvious changes as would occur to a person skilled in this art and as would fall within the scope of the claims.

This application is a substitute for the application filed by Lawrence Skow, Morris Kraus and John Sorenson, Serial No. 345,937, filed Dec. 19, 1919 for radiator core, as joint inventors.

In the drawings:

Fig. 1 is a front elevation of a radiator having a core made in accordance with my invention;

Fig. 2 is a fragmentary front elevation of a radiator core made in accordance with my invention;

Fig. 3 is a section taken on the line 3—3 of Fig. 2;

Fig. 4 is a fragmentary vertical sectional view of the radiator core taken transversely thereof;

Fig. 5 is a fragmentary perspective view of one of the water section wall forming elements; and

Fig. 6 is a similar view of one of the air deflector partition elements.

Referring in detail to the drawings Fig. 1 shows a radiator 7 having a radiator core 8 made in accordance with the present invention. The radiator core is made up of 10 a plurality of sheet metal members pairs of which form water containing chambers or passages and others of which form spacing means or deflector elements between the water containing members. The water containing members are made up of two sheet metal plates that are similar in form, being made in the form shown in Fig. 5, and these are oppositely arranged so that the sides thereof confront each other.

20 Referring to Fig. 5 the members forming the walls of the water chambers are corrugated so as to provide curved corrugated raised portions 9 and straight corrugated raised end portions 10. These alternate 25 with depressed or oppositely corrugated curved central portions 11 and straight end portions 12, the corrugations at 12 being deeper than the corrugations at 9, 10 and 11 so that when the elements are arranged 30 in such a manner that the corrugations 11 of one member rest in the recesses provided by the corrugations 9 of the other member, the portions 12 will contact with the portions 10 in such a manner as to space the 35 two plates from each other throughout the curved corrugated portions thereof from edge to edge.

In Fig. 4 the plates forming the walls of the water channels are referred to by the 40 numeral 13, and it will be seen that in the manner just described water passages or channels 14 are provided between the sheet metal members 13 extending from the top to the bottom of the radiator and forming a 45 tortuous channel from top to bottom. The water channels are so arranged that the curved portions of the walls extend in the same direction for each of the water containing members and these are so arranged that 50 the central portions of the curved part 9 or 11 are higher when in the radiator than the end portions thereof. Thus in Fig. 2 the central portions 15 of the water containing members are shown as being higher than the 55 end portions 16 thereof. Between the water channels air passages 17 are formed and these will have side walls corresponding to the shape of the walls of the water containing members, that is, they will be corrugated and these corrugations will be curved 60 as is shown in Fig. 5. Interposed between the water containing members and located in the air passages are the partitions or air deflector elements 18; one of these is shown 65 in fragmentary perspective view in Fig. 6.

The partition members are made of corrugated sheet metal in a similar manner to the members that form the walls of the water containing members and are provided with curved corrugations 19 and 20 extending in 70 opposite directions. The curvature of the corrugations, however, is always in the same direction just as with the members forming the walls for the water containers, but when these are assembled with the water container 75 elements the corrugations are so arranged that they curve in the opposite direction to those of the water container elements, that is the lowest point of the curve will be in the center and the end portions will be higher. 80 The end portions 21 of the spacing or deflector elements 18 are made straight as in the case of the elements forming the walls for the water containers, and these are corrugated more deeply than the central portions of 85 the sheet thus providing an excess of material in the central portions. The corrugations at 21 are provided with grooves or recesses 22 which are adapted to act as seats to receive the crests of the corrugations 10, 90 so as to seat the parts in proper relationship to each other and hold them in this position while the parts are being soldered together. The ends of the radiator are dipped in solder so that the corrugations 12 of one 95 sheet, the corrugations 10 of another sheet and the portions 22 of the partition member are united throughout the edge portions of the core, while the central portions are spaced as is shown in Fig. 3 so as to form 10 water containing channels or passages 14 between the members 13 and air passages between each member 18 and the adjacent members 13.

It will be noted on an inspection of Fig. 3 10 that the crests of the corrugations 19 do not touch throughout the entire curved corrugated part of the core, but that a slight space is provided between them at 23. Each of the air channels will have a wall on one 11 side that is corrugated and curved so as to have the highest points of the curves of the corrugations upwardly and the other side with the highest points of the curves of the corrugations downwardly, thus forming 11 a channel of constantly varying width and cross sectional outline and in that way providing a tortuous passage for the air so that the maximum cooling effect thereof will be obtained. However, it will be noted 12 on an inspection of Fig. 5 and Fig. 6 that in neither the water container wall forming members nor the members forming the partitions are the curves of the corrugations such that they recurve and thus a passage 13 way is provided that offers considerable resistance to the passage of air therethrough and provides a large amount of wall area for the air passages and the water containing elements, while at the same time clog- 13

ging of the air passages is prevented as any foreign matter would readily pass therethrough as there is no reentrant portion in which such foreign matter could lodge. In 5 case any foreign matter should become lodged in the passages it can be readily removed by floating the same out with water or forcing it out with steam or compressed air as the passages are such that the foreign 10 matter can be easily forced out of the same as the curves of the corrugations are not so sharp as to prevent this. As none of the various elements touch each other, except at the edge portions thereof, a radiator is 15 provided that has a great degree of flexibility and which can expand considerably without any harm thereto that would result in leakage. In the case of freezing the elements 13 would expand so as to separate 20 from each other further and would approach the corrugations 19 or 20 of the spacing elements and with further expansion would contact with these corrugations and would tend to flatten them. However, due to the 25 manner in which the spacing or partition elements are constructed with an excess of material in the curved corrugated part thereof these have a certain amount of resiliency and tend to return to their normal position, consequently when the ice formed in 30 the frozen radiator thaws the partitions or spacing elements will tend to return the members 13 to their original position wherever the two parts are in contact. While the 35 spacing such as at 23 would probably not exist throughout the radiator after such freezing has taken place as would distort the partition member the radiator would be restored so nearly to its normal position that 40 the freezing will do no harm thereto even where the radiator is frozen solid and no leakage results.

Having thus described my invention what I claim and desire to secure by U. S. Letters 45 Patent is:

1. In a radiator core a plurality of spaced water container members providing air pas-

sages therebetween, each of said water container members comprising a pair of sheet metal members provided with curved corrugations, and sheet metal partitions in said air passages provided with corrugations curved in a direction opposite to those of the water container members. 50

2. In a radiator core a plurality of spaced water container members providing air passages therebetween, each of said water container members comprising a pair of vertically extending sheet metal members provided with corrugations curved downwardly 60 from the center to the edge portions of said sheet metal members, and sheet metal partitions in said air passages provided with corrugations curved in a direction opposite to those of the water container members. 65

3. In a radiator core a plurality of spaced water container members providing air passages therebetween, each of said water container members comprising a pair of vertically extending sheet metal members provided with curved corrugations and provided with means at the borders thereof for spacing said members to provide a water passage extending from top to bottom and from end to end of said core, and sheet 70 metal partitions in said air passages provided with corrugations curved in a direction opposite to those of the water container members. 75

4. In a radiator core a plurality of spaced water container members providing air passages therebetween, each of said water container members comprising a pair of similar oppositely facing sheet metal members provided with curved corrugations, and sheet 85 metal partitions in said air passages provided with corrugations curved in a direction opposite to those of the water container members. 80

In witness whereof, I hereunto subscribe 90 my name this 21st day of September, A. D. 1920.

JOHN SORENSEN.
